SEWING MACHINE

John P. Weis and Frederick F. Zeier, Nyack, N. Y., assignors to Wilcox & Gibbs Sewing Machine Company, New York, N. Y., a corporation of New York

Application January 21, 1935, Serial No. 2,806

30 Claims. (Cl. 112—220)

This invention relates to improvements in sewing machines, and particularly to a novel and highly efficient main driving mechanism wherein inertia is minimized and desirable very high speeds are made possible. It particularly relates to auxiliary or supplementary driving mechanisms adapted to easily and quickly convert an open standard sewing machine into a special sewing machine for actuating one or more auxiliary or supplementary operation units such as rufflers, trimmers, and the like.

One of the principal objects is the provision of improved main driving mechanism, for synchronously operating cooperating needle driving, loop forming, lubricating and work feeding mechanisms, which will be sturdily supported and well lubricated, so that it will have a long life and freedom from repair.

Some of the aims in connection with this object are to provide a driving mechanism capable of operating at variable speeds, from minimum to maximum within the limits and possibilities that the sewing threads or the materials will endure (e. g. speeds of 5,000 R. P. M. in the formation of stitches for the seams of garments and other sewed articles; in the placing of stitches for ruffling, tucking, shearing, gathering, and similar requirements; and in the formation of ornamental and decorative stitches) and to do this 20 silently and smoothly at all speeds, with a minimum of vibration and maintenance cost.

Other aims in connection with this objective is to provide an improved operating mechanism with a minimum of inertia and one capable of quick acceleration. This aim is important since considerable time may be lost in starting and stopping if the various operating parts are long or heavy. The loss of time and production may amount to considerable in a days run of a machine that should be started and stopped between ten and fifteen thousand times in a working day of eight hours. Ease of control, or operation and the minimization of fatigue to the operator are of vital importance.

Several novel features are embodied in the structure developed to meet this object and the complementary aims. One of these is the provision of a main frame with a hollow trunk adapted to locate and support substantially all 50 the main driving mechanism, and which is open on three sides to facilitate initial assembly and adjustment and to make subsequent or field repairs and adjustments easier, but adapted to be closed later for thorough lubrication of all moving parts therein.

The main driving mechanism is particularly novel for it permits close spacing of the feed and looper parts in the under or work supporting arm which is desirable in order to feed small diameter cylindrical work therearound, and because it is located substantially central relative to the needle, feeding, and loop forming mechanisms thereby minimizing inertia to increase the speed and performance of the machine. Another advantageous aspect of the main driving mechanism 10 is that one main crank shaft may be used equally well for driving both transverse and longitudinal type loopers. By having the main drive shaft paralleling the other main operating rods of the looper and other cooperating mechanism, a minimum of driving interponents is required. The central location of the hand wheel adds to the convenience of operation for the operator, affording ease of operation, and eliminating the fatigue of reaching too far for positioning the needle, 20 threading, stopping, and other requirements of the hand wheel. Also, the central location of the main drive shaft permits the use of exceptionally short crank shafts and pitman connections to the various driven parts, and thereby 25 reduces inertia, vibration, and noise.

Although there have been previous efforts to provide a main drive shaft intermediate the upper and lower arms, such efforts usually resulted in a shaft projecting at right angles to the arms and with a handwheel inconveniently located at the front of the machine. The drive and handwheel at the middle and side of the machine as provided by the present invention may be grasped 30 and manipulated much more advantageously and 35 will not impede the material or the operator's work handling movement at the front of the machine.

It is an important object of the present invention to provide a main driving mechanism with 40 a plurality of associated driving connections which may in large part be assembled extraneously of the machine in order to facilitate the final assembly operation of the complete machine; viz., making it unnecessary for the operator to perform many small operations within 45 the confines of the main frame where his movements would be impeded, and thereby considerably increasing the output or decreasing the manufacturing costs of the complete machine 50 and insuring a better final fitting and relationship of the various interconnected or associated operating parts.

Features in connection with this object include a preferably solid main drive shaft with 55

a plurality of substantially equal length crank arms which may be assembled thereto and then passed through a large opening in a side wall of the main frame into an operative position within the frame, with a novel bearing support therefor, whereupon the outer or free ends of the crank arms or the links, arms, and other connections thereon may be connected to their respective associated mechanisms. A complementary feature includes the provision of a main frame with a trunk having an opening and a suitable cover plate on the bottom and/or the top of the trunk to facilitate initial assembly of the main drive shaft and its associated crank arms to the trunk and/or to facilitate assembly of the crank arms to associated mechanisms; to repair; and to make adjustments.

Heretofore it has been the usual practice to provide standard sewing machines for regular or plain stitching operations and entirely separate special purpose machines when it is desired to make ornamental stitches, to ruffle, trim, effect auxiliary feeding and divers other ancillary operations. These special machines were usually provided with extra operating rods supported on lugs projecting from the front or rear walls of the top arm, operated very indirectly (usually from the needle operating rod which was in turn driven by a main drive shaft in the lower arm) and because of this general design impeded the operator and because of the several indirect driving connections increased the possibility of breakdown or operating trouble.

In passing, too, it should be noted that in many of the previous efforts to overcome the necessity of special machines for additional or special operations, it has been the usual practice to connect attachments to an existing machine in a make-shift manner and to operate these from the outer ends of a light needle operating rod in the upper arm or from light and in many instances previously overtaxed looper and feeding rods in the lower arm. In making such additions to these machines several very marked disadvantages resulted, for in addition to overloading light operating parts and causing undue strain on the machine and frequent breakdowns, this plan had the marked disadvantage of usually making it necessary to secure the attachments to the cloth plate of the machine, thereby hampering the operator considerably and increasing the manufacturing costs of the article being sewed.

In some other forms operating rods supported in auxiliary bosses projecting from the front and/or back of the upper arm of the sewing machine were provided which tended to impede the operators movements at the sewing machine and which in practically every instance were in the nature of auxiliary shafts driven from an upper needle operating shaft, the latter in turn very often being an intermediate shaft driven from a main shaft in the lower arm or in the base of the machine.

It is an important object of the present invention to provide a sewing machine making possible the addition of various auxiliary operation units to the cloth plate in the well known manner but to operate such units by a substantially direct drive from the main drive shaft, rather than indirectly from intermediate operating rods of the needle, looper or feeding mechanisms.

It is another very important object of the present invention to provide a sewing machine which will normally be entirely free of exposed driving connections for auxiliary operating instrumen-

talities, to have the appearance of the plain or standard sewing machine and more particularly so that the operator will not be impeded in any way, but, which may be easily and quickly provided with various auxiliary operation units for performing divers special operations.

Features in connection with this last object are the provision of auxiliary operation units, and a support and driving connections for these auxiliary units, all of unique and highly advantageous form; adapted when the machine is so converted, to provide a machine which is comparatively free of external operating instrumentalities which would tend to impede the operator's normal movements at the machine. Also, in its preferred form, the units and the supports, and the driving connections therefor are such that a substantially direct driving connection is obtained.

On some sewing machines and on some types of work it is desirable to add auxiliary devices to perform auxiliary operations; but, this was impossible on some sewing machines because only reciprocatory or oscillatory driving shafts were available for use with auxiliary devices, when a completely rotary drive shaft was required for operating the necessary apparatus for the auxiliary operation.

It is an object of the present invention to provide a sewing machine in which a very efficient rotary drive shaft is available for driving auxiliary operation units, even though the other driving shafts for the regular sewing and feeding operations are of the oscillatory or reciprocatory type.

Other objects, features, and advantages will appear hereinafter.

The detailed description which follows, in order to facilitate a quick understanding of the machine of the present invention and its mode of operation, has been broken down into various titled sections. The present invention is not limited to the details of construction and arrangement of parts illustrated in the accompanying drawings for it is capable in whole or in part of other embodiments and the phraseology employed is for the purpose of description and not of limitation.

Frame and general structure

The present invention comprises a main frame 30 with an upper arm 31 supporting a needle operating mechanism 32 and a lower arm 33 for locating and supporting looper and feeding mechanisms 34 and 35 respectively and forming a work support 36 while a vertical trunk 37 locates and supports the upper and lower arms relative to each other and locates and houses a main driving mechanism 38.

Although the upper arm 31, lower arm 33, and the trunk 37 may, within the purview of the present invention be made as separate units, secured to each other by screws or the like, they are preferably made of an integral one piece casting, as shown, for simplicity, ease of cleaning, to prevent looseness and misalignment of parts, and for economy in manufacturing cost.

Upper arm and needle operating mechanism

In its present preferred form the upper arm 31 is preferably of rectangular cross section, hollow and tapering through its length, to form a chamber 39 having transverse walls 40 and 41 with bearings 42 and 43 supporting a needle operating rod 44 for oscillatory movement. At the right hand end as viewed in Figs. 1, 2, and 5 the rod 44 is provided with a yoke 45 adjusted and secured thereto with a bolt 46 and through an integral arm 47 and a ball and socket joint 48 being connected to a crank arm 49 and to the associated main driving mechanism 38.

At its outer end the rod 44 is provided with an arm 50 having a link connection 51 to the upper end of a needle bar 52 to reciprocate the latter and a needle 53 carried thereby vertically in suitable bearings 54. A finger 55 on the upper end of the needle bar slides in a suitable slot 56 in the front of a head 57 section of the upper arm 31 to insure steady operation and is provided with a thread take up plate 55'.

The arm 50 is provided with a yoke 58 and screw 10 59 to adjust the needle vertically relative to the work support 36. This yoke 58 and the yoke 45 at the opposite end of the rod 44 engaging the adjacent bearings 43 and 42 respectively prevent the rod from shifting lengthwise.

The head 57 also supports a presser bar 60 having a presser foot 61 in its lower end in bearings 62 in the usual manner. A flat spring 63 connected to a pin 63' engages a ball 64 in the upper end of the presser bar 60 to press the foot 20 61 toward the underlying work support 36 and feed dog 65, while a screw 66 may be turned to impart any desired degree of pressure.

Hand and foot controls 67 and 68 respectively are provided to move the presser foot 61 relative 25 to the lower arm 36, both being associated with a yoke 69, see Figs. 1, 1—A, 2, and 4 tightened in the desired position on the presser bar with a stud 70 and having a horizontal finger 71 sliding in a slot 72 to prevent the presser foot from rotating. The hand control 67, best seen in Figs. 1 and 1—A comprises an overthrow cam 73 pivoted on a stud 74 on an end cover plate 75 engaging the stud 70. In one position a low point 73a of the cam allows the presser foot to be moved into operative relation with the work support by the spring 63 and in another position the high point 73b of the cam lifts and maintains the presser foot in a raised inoperative position relative thereto.

The foot control 68 for lifting and lowering the presser foot 61 includes a lever 76 secured to a cross bar 77 in the upper arm engaging a slot 78 in the vertical finger 79 while the cross bar 77 is provided with an outer lever 80 to which any usual foot pedal structure may be secured as by the hole 80'. When the pedal is depressed the lever 80 is pulled down and the lever 76 is raised, and the latter through its connection with the finger 79 and presser bar 60 raises the presser foot 61.

The head 57 is, according to the present invention, constructed in a unique manner and provided with very novel auxiliary operating and driving mechanisms. Because the function and operation thereof are in the main ancillary or supplementary to standard or regular operations detailed description will be given after the main driving, feeding, and other regular or standard operating mechanisms are described.

Lower arm

Primarily the lower arm 33 comprises longitudinally extending front and rear walls 81 and 82, with transverse end and intermediate walls 83 and 84 respectively adapted to support an interchangeable wide cloth plate 85 (and narrow cloth plate, not shown herein but indicated by dot-and-dash lines 85') and to interchangeably support an adaptor plate 86 and throat plate 87 dependent upon needle, stitch, article, and feed 70 requirements.

The lower arm 33, interchangeable cloth plates and supporting structure for converting the machine from a feed across to a feed around the arm machine and other associated novel 75

features are more fully disclosed and claimed in a co-pending application Ser. No. 750,259 filed October 27, 1934.

The lower arm 33 also supports the feeding mechanism 35 comprising a feed dog 65 secured to a carrier 88 by a screw 89. Operative work engaging and work moving relationship between the feed dog 65 and presser foot 61 is accomplished by an oscillating arm 90 secured to a feed lifter rod 91 by a yoke 92 through a flat spring 93 lifting the feed dog 65, and by a rocking finger 94 secured to a feed rocker rod 95 by a yoke 96 and through a spring 97 connected to the carrier 88 reciprocating the feed dog. The feed lifter and rocker rods are supported for oscillatory movement in the transverse end wall 83 of the lower arm 33 and in side walls 98 and 99 of the trunk 37 while collars 100 and 101 prevent endwise movement.

Driving connections 102 and 103 associated with the main drive mechanism 38 and including arms 104 and 105, see Fig. 3 particularly, secured to the rods 91 and 95 respectively, actuate the feed dog 65 in timed relation with the reciprocation of the needle 53.

The feeding mechanism 35 forms the main subject matter of a copending application Ser. No. 747,871 filed Oct. 11, 1934 where it is much more completely described.

The lower arm 33 also locates and supports the looper mechanism 34 which cooperates with the needle 53 or the complete needle operating mechanism 32 to form what may be termed the sewing mechanism. Although only one form of looper mechanism (transverse type looper) is illustrated herein, for simplicity of drawings and description, it should be understood that it is within the purview of this invention to use the novel main driving mechanism 38, auxiliary driving mechanisms, and associated auxiliary operation units driven thereby, forming the main subject matter of this invention, with other types of looper mechanisms (for example the longitudinal and universal loopers) disclosed in a co-pending application (Serial No. 745,343, filed Sept. 24, 1934).

The herein illustrated form of looper mechanism 34 comprises a looper carrier 106 interchangeably supporting a looper 107 pivotally mounted on a stud 108 for needle loop taking and shedding travel relative to the needle 53, in a direction transversely relative to the line of feed, and pivoted on a sleeve 109 between collars 110 for needle avoiding movement longitudinally relative to the line of feed. This four-motion travel to the looper 107 is accomplished by an upper reciprocating rod 111 and a lower oscillatory rod 112 and connection 200 mounted in suitable bearings 113 and 114 respectively in the end and intermediate transverse walls 83 and 84 of the lower arm 33 and the side walls 98 and 99 of the trunk 37, the upper rod being reciprocated by a driving connection 115 and the lower rod being oscillated by another driving connection 116, both associated with the main drive shaft.

65 Main driving mechanism

The main driving mechanism 38 is of very novel construction and should be particularly noted. It comprises a main drive shaft 117 preferably made of one-piece construction, with a plurality of cranks A, B, C, D, and E thereon, forming and supporting ball and socket connections 118, 119, 120, 121, and 122, see Figs. 1 and 2 particularly, with crank arms 49, 123, 124, 125, and 126 which may be secured in place thereon by merely tight-

ening the usual caps and screws. These ball and socket connections are preferably, through screw and lock nut connections associated with the crank arms to complete the driving connections 48, 115, 116, 102, and 103 to the needle operating mechanism 32, to the looper mechanism 34, and to the feeding mechanism 35 respectively.

Now, it should be particularly noted that, according to the present invention, it is possible to affix and adjust the ball and socket connections 118 through 122 to the cranks A through E extraneously of the frame 30 where it is possible to get at these parts advantageously, viz., without hindrance. In sewing machines where the parts are operated at very high speeds it is important to have the bearings as tight as possible in order to prevent knocking or vibration and yet to have the bearings free enough so that they will not freeze after being operated for a while at high speed and during the subsequent heating of the operating parts. Thus, this feature of the present invention provides a double advantage of marked economy in manufacturing assembly cost and the assurance of just the right fit of the various bearings on the main drive shaft 117. Links, ball and socket connections, etc. on the outer ends of the crank arms may likewise be advantageously assembled extraneously of the trunk 37 as will be described more fully hereinafter.

The main driving mechanism 38 includes a small ball bearing 127 adapted to fit upon one end of the main drive shaft 117 and to be located and supported in any suitable bore 128 in the side wall 98 of the trunk 37, and at its opposite end is provided with another ball bearing 129 having an inner race slid upon the shank 130 of the main drive shaft and held in place thereon between a shoulder 132 and a hub 133 on a main driving pulley 134 and the outer race clamped in a recess 135 of a large plate 136 with a flange 137 and screws 138. A flange 139 on the plate 136 engaging with a suitable shoulder on the driving pulley serves to prevent oil leakage, and in addition any suitable and conventional oil retainer may be provided in the cavity between the ball bearing 129, hub 133, and flange 139 of the plate 136. A screw 140 holds the drive pulley 134 in place on the shaft.

The ball bearings 127 and 129 may be assembled to the main drive shaft 117 extraneously of the machine prior to final assembly; but preferably, in order to facilitate assembling the main driving mechanism 38 including the main drive shaft 117 and the associated crank arms A through E, in the trunk 37, the bearings are assembled to the shaft 117 and to the trunk 37 as shown after the shaft and associated cranks are put in place within the trunk. The outer plate 136 is preferably located relative to the trunk by a shoulder 141 fitting within a suitable bore 142 and a flange 143 thereon being clamped in place by suitable screws 144, and the bearing 127 at the other end of the shaft is held against the shoulder 145 by a cover plate 146 as shown in Fig. 1 or by a similar cover plate 146' as shown in Fig. 1-B held in place by suitable screws 147.

The large bores 128 and 142, and indirectly a receding section 148, make it possible to tilt the driving mechanism at a considerable angle in order to facilitate placing the various crank arms within the trunk and after they are so placed the main drive shaft may be straightened and be located substantially centrally in order to complete connection of the bearing to the walls 98 and 99. Also, the large opening 142

makes it possible to drop the whole main drive mechanism 38 relative to the main frame and below the normal axial location of the main drive shaft so that the upper crank rod 49 may be passed through the opening 142 in order to get the upper crank arm into the trunk and to lift and tilt the upper crank arm and the main drive shaft after the crank arm 49 is in the trunk in order to get the crank arms 123 through 126 within the trunk.

After the main driving mechanism is so located assembly of the connection 48 to the needle operating rod 44 may be easily accomplished through a top opening 149, and all the lower connections may likewise be easily accomplished through the lower opening 150. For example, a ball and socket connection 151 including the usual cap and screws at the lower end of the crank arm 123 is made to a bell crank 152 pivotally mounted on a cross rod 153 which at its lower end has a ball and socket connection 154 to the upper reciprocating rod 111. If preferred, the bell crank 152 and connection 151 may be assembled to the main driving mechanism 38 extraneously of the machine, in which event connection of the cross rod 153 and lower ball and socket joint 154 is completed subsequently to placing the main driving mechanism 38 in the trunk. Also, a ball and socket connection 155 including the usual cap and screws may be secured to an arm 156 in order to impart oscillatory movement to the lower rod.

Similar operating connections are effected to the feeding mechanism 35 through completing a ball and socket connection 157 including the usual cap and screws to the arm 104. The crank E is connected to an arm 105 carried by the feed rocker rod 95 as by a pin 159 passed through the link 160.

Preferably the main driving mechanism 38, as it is assembled extraneously of the machine, includes the bell crank 152, the arms 156, and 104, and also the crank 126 with a slot 161 adapted to receive a slide 162 of a feed regulating mechanism 163 and with the link 160 and arm 105 thereon of the feed rocker rod driving connection 103 whereupon it is only necessary for the assembler to complete the ball and socket connection 48 to the upper needle operating rod 40 and to tighten the yoke 164 with screws 165 to the lower oscillatory rod 112. In like manner the feed lifter rod 91 and feed rocker rod 95 may be slid lengthwise in the frame into yokes 166 and 167 whereupon the latter two may be tightened in place with screws 168 and 169. The oscillatory rods 91, 95, and 112 are held against longitudinal movement in the frame by collars 100, 101, and 170 respectively as shown in Figs. 1 and 3.

Broadly, the feed regulating mechanism includes a sleeve 174 secured in lugs 175 and 176 including a regulating screw 177 with a knob 178 at its upper end adapted to move a slide 179 lengthwise thereof, the slide carrying the pivot slide block 162 movable in the aperture 161 in the crank arm 126. When the pivot 162 is located high in the slot 161 a relatively large movement is imparted to the lower end of the crank arm in order to effect a considerable rocking or feeding movement to the feed dog 65, and when it is located lower in the slot, a relatively shorter movement and feed is imparted. The slide block may be simply slid into the aperture 161 when the main driving mechanism 38 is placed within the trunk 37. A pointer 180,

carried by the slide 179 is moved past a graduated scale on a transparent disc 181 on the trunk in order to indicate the extent of feed or number of stitches per inch.

The feeding and the feed regulating mechanisms 35 and 163 are much more completely described in a co-pending application Ser. No. 747,871 filed Oct. 11, 1934 wherein its novel features of construction are claimed.

After the driving mechanism 38 and associated parts are properly assembled the upper and lower cover plates 171 and 172 respectively are secured in place, thereby changing the trunk 37 into a substantially oil tight chamber 37'. Oil may be added through the top opening 149 and may be drained through the pet cock 173 in the bottom plate 172.

This main driving mechanism 38 located substantially midway between the upper and lower arms and substantially parallel therewith has the important advantage of providing short substantially equal length driving connections to the needle operating mechanism 32 in the upper arm 31 and to the looper mechanism 34 and the feeding mechanism 35 in the lower arm 33 thus reducing the mass of the individual parts moved, reducing the inertia, and thereby making possible desirable high speed operation. Also, it has the advantage of providing a handwheel control 182 at a point sufficiently raised from the table to prevent the operator from skinning his knuckles, and yet not high enough to tire the operator as occurs in those machines where the handwheel control is associated with a main drive shaft supported in the lower arm 33 or in the upper arm 31. The centrally located hand control on the side of the machine rather than on the front of the machine also has the advantage of making it easier for the operator to grasp and move the mechanism and of lessening the possibility of hindrance to the work and to the operator's movements at the front of the machine.

Lubrication

Of particular importance, too, the centrally disposed drive shaft 117 makes possible the very efficient lubrication of substantially all of the moving parts within the trunk 37 by spray, gravity, and capillary action. This advantage may briefly be described by reference to Figs. 1 through 5 wherein there is disclosed a pump 183 driven from the main drive pulley by a belt 184 adapted to draw oil from a reservoir 185 in the bottom of the chamber 37' and to force it upwardly through an eduction tube 186 and to expel it against the underside of the cover plate 171 and to an upper container 187. Some of this oil flows down through a channel 188 into suitable oil entrance holes 189, see Figs. 1 and 2 respectively into the bearing 42 and rod 44 to lubricate bearings of 60 the needle operating mechanism, and from the lip 190 drops onto the ball and socket connection 48 to lubricate the latter. The bulk of the oil, however, flows from the upper container 187 through a pipe 191 into an intermediate container 192 having outlet ports 193 overlying the cranks A through E. Some of the oil from the latter source drops directly into funnels 194, thence through the ball and socket connections 118 through 122 through suitable holes in the crank arms 123 through 126, to the lower associated bearings. Some of the oil flows down over the side walls or is thrown about by the various operating connections into the ball bearings 127 and 128, into the pan 195 for lubricating the bell crank 75

152, and likewise some of the oil flows over the side walls 98 and 99 or drops by gravity through holes 196, 197, 198, and 199 in the rods 111, 112, 91, and 95 respectively in order to lubricate the 5 bearings 113 and sleeve 109 of the upper rod 111, to lubricate the bearings 114 and connection 200 of the lower rod 112, and similarly to lubricate the bearings 201 and 202 throughout the length of the feed lifter and rocker rods 91 and 95 respectively. 10

The various details and certain modifications of this advantageous lubricating system and mechanism are much more completely described and claimed in a co-pending application Ser. No. 15 755,372 filed Nov. 30, 1934. It is thought that the present brief description is sufficient to indicate the advantageous lubrication in part made possible by the present main driving mechanism forming the main subject matter of the present 20 patent application.

Auxiliary driving mechanisms

A particularly novel feature of the present invention is the provision of a very efficient and 25 extremely desirable auxiliary driving mechanism 204 and support 205 whereby the sewing machine may be a plain substantially standard sewing machine normally, without outside lugs and auxiliary shafts, and wherein one or more auxiliary 30 operation units for performing special operations may be added to and operated on the machine both easily and quickly.

It is frequently desirable in certain sewing operations to trim the material, to provide auxiliary 35 feeding apparatus for extra thick or unwieldy materials, to effect special stitch formations, to move plies of material relative to each other, to ruffle, and to perform other ancillary operations. Heretofore these operations were usually done on 40 specially built machines or on machines with make-shift attachments inefficiently driven from looper, needle and other intermediate operating rods.

The present invention provides several unique 45 and highly efficient structures for accomplishing these and like functions in a single machine with highly desirable substantially direct driving connections and in a manner to prevent hindrance or obstruction to the operator or to the work. In 50 its simplest form, illustrated in Figs. 1, 4, 22, and 23, it comprises a connection 206 at one end of the main drive shaft 117 adapted to receive an extension drive shaft 207. Normally the bearing 127 is enclosed at this point with a plain full cap 146 as shown in Fig. 1-B. However, it may be 55 at all times enclosed by a cap 146 with a bore 208 as shown in Fig. 1 if preferred.

Various extension rods (for example the extension rod 207 of Fig. 23 ending short of the support 60 205 on the upper arm 31, and the extension rod 207' of Fig. 1 entering the support 205, or the like), may be provided and may be driven by the main drive shaft 117 as through the adjustable driving connection 206. The latter connection, 65 in its present preferred form, includes an intermediate extension 209 having a screw connection 210 to the main drive shaft as shown in Fig. 1 and having a tongue and slot connection 211 including a tongue 212 on the shaft 207' and a slot 212' on the intermediate extension 209 with a screw 213 adapted to prevent the tongue from shifting laterally in the slot 212' and to clamp it against lengthwise movement therein. 70

This tongue and slot connection 211 has the 75 advantage of making it possible to assemble the

extension drive shafts 207 and 207' to the main drive shaft 117 without interference by the support 205 and permits axial shifting of these extension shafts for special conditions.

Figures 22 and 23 disclose one form of device 5 214 which may be operated directly from the main drive shaft 117 rather than through a very indirect hook-up with a reciprocating needle bar, or from an auxiliary operating rod on the back or on the front of the machine, the means usually 10 resorted to for operating a trimming device close to the needle. This device includes a base 214' adapted to be secured to the work support 36 with screws 215 and having a standard 216 provided with a channel 217 housing a slide 218 for 15 vertical reciprocatory movement under a cover plate 219 and having at its lower end a cutter carrier 220 capable of lateral shifting relative to the line of stitching by a screw and slot connection 221 and through another screw and slot 20 connection 222 making possible vertical adjustment of a cutter blade 223 adapted to cooperate with a lower cutter 224 which may, as shown, be formed in the throat plate 87.

Reciprocation of the slide 218 is accomplished 25 by the provision of an eccentric 225 secured to the extension shaft 207 by a screw 226 as shown in Fig. 23, the collar in turn having a concentric section 227 fitting into a suitable bearing 228 of the standard 216 in order to locate and support 30 the outer end of the extension shaft. Each rotation of the extension shaft rotates the eccentric and reciprocates the slide 218 and cutter 223 once relative to the cooperating cutter 224 to trim the work a predetermined distance from the line of 35 stitching as it is fed.

Thus it will be seen that the present invention provides a direct driving connection between the main drive shaft 117 and the trimming unit 229 in order to effect a sturdy or strong and yet 40 smooth operating condition, and so that no adverse strains are imposed upon remote light or weak operating instrumentalities.

It is within the purview of the present invention to use this direct type of drive with other 45 attachments secured to the cloth plate 85 or work support 36, the trimmer shown in Figs. 22 and 23 being merely illustrative of such use and being sufficient to teach others skilled in the art the method of using this highly efficient direct 50 drive for other types of devices secured to the work support plate.

Although this mechanism just described has the advantage of providing a direct drive it does have the disadvantage of hindering the operator's 55 movements and obstructing the passage of large pieces of work over the work support. In order to overcome this very marked disadvantage the present invention provides a very novel driving mechanism and a support for divers auxiliary 60 operation units.

In its present preferred form this auxiliary driving mechanism 204 and support 205 for the various operating instrumentalities includes a horn 205' having front, rear, and side walls 230, 65 231, 232, and 233 at the outer and lower end of the upper arm 31 as shown in Figs. 1 and 4, and 6 through 16 particularly.

Preferably these walls 230 through 233 are machined to provide a good supporting surface 70 and are each provided with a shoulder 234 to assist in locating operating units in place thereon. Screw holes 235 in diagonally opposite corners, as may be seen in Figs. 6 and 9 are also provided to hold units on the individual walls. As shown, 75

three walls 230, 231, and 232 of the horn 205' are made integral with the upper arm to provide a chamber 236 and the fourth wall 233 is preferably formed on a cover plate 75 secured to the outer end of the upper arm by screws 75'. This cover plate facilitates assembly and adjustment of various parts in the upper chamber 39 of the arm 31 and in the lower chamber 236 in the horn. The lower chamber 236 also forms a housing adapted to support a transmission mechanism 237 including what is preferably termed a lower horn shaft and an upper horn shaft 238 and 239, the former being held against axial movement by a flange 240 and collar 241 and the latter being held against axial movement by collars 242 and 243 at opposite ends thereof. These two shafts carry cooperating right angle helical gears 244 and 245 held in place by suitable screws. The shafts 238 and 239 are provided with projecting ends adapted to receive gears, cams, and other driving elements and are driven in unison by the extension shaft 207' having the tongue and slot connection 211 with the main drive shaft 117 at one end and having a spline connection 250 in a suitable bore 251 of the lower horn shaft 238 as shown in Figs. 1 and 1-C in order to rotate the latter in unison with the main drive shaft.

The spline connection 250 at one end of the extension shaft and the tongue and slot connection 211 at its other end enables an assembler or operator to quickly convert the machine from a plain sewing machine to a machine capable of driving one or more auxiliary operation units both easily and quickly without disassembling or changing any of the other regular operating mechanisms such as the main drive, needle operating, feeding, and looper mechanisms 38, 32, 35 and 34 respectively. Since the shaft 207' is located five or six inches above the cloth plate 85 the work support is entirely free for the operator's hands and for the passage of materials, and because it is not mounted exteriorly upon the frame it does not hinder or obstruct the operator in his movements around the machine. Also, the direct drive between the main drive shaft 117 and the transmission mechanism 237 provides a sturdy positive operating condition without undue strain on other remote operating elements, as would occur if the drive was effected through intermediate operating rods used for other purposes in the sewing machine. The gears 244 and 245 may be covered and the chamber 236 may be partly filled with grease of the proper consistency when the machine is assembled, and the chamber thus serves to keep the gears lubricated over a long period of time after the cover plate is secured in place with screws. A modified form of auxiliary driving mechanism 204' is also shown in Figs. 18 through 21 and is described in detail hereinafter.

Auxiliary operation units

In order to illustrate the novelty and utility of the present invention, various of the operating units to be used in conjunction therewith will now be described. At least one auxiliary operation unit for each of the sides 230 through 233 is illustrated and described herein.

Figs. 6 and 7 illustrate one form of auxiliary operation device comprising a simple form or ruffling unit 252 which may be used to change the machine from a regular sewing machine into a ruffler type sewing machine in but a moment. It comprises a base member 253 adapted to be secured to the front wall 230 of the horn 205'

with screws 254 entering tapped holes 235. The base is provided with arms 255 supporting a cross pin 256 for rotary movement but held against axial movement by a head 257 and collar 258. An arm 259 is secured to the pin 256 with a yoke 260 and at its lower end is provided with a flexible ruffling blade 261 adapted to engage materials on the work support 36 or throat plate 87 and to ruffle them a predetermined extent relative to the presser foot 61 and thence to move the ruffed material under the presser foot when the feed dog 65 is actuated, in the well known manner of ruffling devices. A coil spring 262, between a pin 263 on the arm 259 and a hook 264 on the lower finger, yieldingly maintains the ruffling blade in operative engagement with the work support.

Oscillatory movement of the arm 259 and resultant back and forth ruffling movement of the blade 261 is accomplished with novel form of drive including an arm 265 secured to the pin 256 with a screw 266 and having an adjusting screw 267 capable of movement toward and from the upper arm 31. This screw is provided with a ball 268 at its front end and with an indicator plate 269 at its rear, and a crank arm 270 having an upper ball and socket connection 271 to the screw 267 and having a lower ball and socket connection 272 to an eccentric 273 secured to the projecting end of the upper horn shaft 239 with a set screw 274, serving to oscillate the arm 259 and finger 261 once each time the needle 53 is reciprocated. By shortening the distance between the ball 268 and the upper arm 265 a relatively greater movement is imparted to the lower arm 259 and finger 261; whereas, when the distance is increased a relatively smaller travel is imparted to these two parts with the one eccentric 273. The device may be removed from the sewing machine by merely loosening the set screw 274 from the shaft 239 and by removing the two holding screws 254.

Figures 8 and 9 disclose an auxiliary trimming unit 276 adapted to be secured to the inner side wall 232 of the horn 205'. It comprises a base 277 adapted to be secured to the wall 232 with screws 254 entering tapped holes 235 and is provided with a channel 278 adapted to receive a reciprocating slide 279 held therein by a top plate 280 and screws 281. At its lower end the slide 279 is provided with a cutter carrier 282 capable of adjustment transversely relative to the line of feed in a screw and slot connection 283 where it may be clamped in desired position. At one end the carrier 282 is provided with a screw and slot connection 284 for locating and holding a cutter 285 in desired vertical position. This cutter cooperates with a mating cutter 286 preferably formed in the throat plate 87. An eccentric collar 287 is passed through a suitable aperture in the top plate 280 and base 277 and into an elongated slot 288 in the slide 279 in order to reciprocate the latter. This eccentric is secured in any desired arcuate position on the extension shaft 207' with a set screw 289 and through rotation of the extension shaft 207' the main drive shaft 117 reciprocates the cutter 285 once each time the needle is reciprocated.

This trimming unit 276 in general is somewhat similar to that shown in Figs. 22 and 23 and hereinbefore disclosed in detail, but has the advantage of not obstructing the operator's fingers near the line of stitching and of allowing the work support 36 to remain entirely free so that wide pieces of material may be stitched and sev-

ered, which is of course impossible when a trimming device is secured to the work support.

Figs. 10 and 11 illustrate another auxiliary operation device comprising a form of top thread controlling unit 290 which may be secured to the rear wall 231 of the horn 205', for forming novelty stitches in the manner disclosed more completely in the Weis Patents 1,961,950 and 1,961,951 granted June 5, 1934. It comprises a base 291 adapted to be secured to the rear wall 231 with screws 254 and provided with a thread carrier 292 therein secured in a lever 293 pivoted on a stud 294 to be oscillated relative to the reciprocating needle 53, or needles.

Another lever 295 is pivotally mounted on a stud 296 of a base member 291 and is provided with a U shaped slot 297 adapted to embrace an eccentric 298 secured to the projecting end of the upper horn shaft 239 with a screw as shown in Fig. 11 and has a tongue 295' engaging a U shaped slot 293' in the lower lever 293. A pivot stud 296, capable of vertical movement in a slot 299, provides an adjustable pivot for the lever 295 in order to vary the extent of movement imparted to the lower lever 293 and thread carrier 292, even though the same eccentric 298 is used.

Thus, Figs. 6 through 11 illustrate three different forms of auxiliary operation units 232, 276, and 290 adapted to be secured to three different sides of the upper arm 31 or the horn 205', and all three of these devices may be on the sewing machine at the same time and operated in desired unison with the regular sewing and feeding mechanisms.

Figs. 12 and 13 disclose another auxiliary operation unit in the form of an auxiliary feeding unit 300 adapted to be secured to the outer side wall 233 of the horn 205' and to be operated by the lower horn shaft 238. It comprises a base member 301 secured in place with holding screws 254 entering tapped holes 235 in the wall 233. A sleeve 302 with eccentric 303 and 304 is secured to the lower horn shaft 238 as by a screw 305. The eccentric 303 accommodates a collar 306 having a spring connection 307 to a feed dog carrier 308, as shown in Figs. 12 and 13. The carrier is provided with an upper feed dog 309 secured in place with a screw 310 and reciprocated by a U shaped channel 311 in a lever 312 which has an intermediate pivot 313 in the form of a stud adjustable vertically in a channel 314 and having at its lower end a ball and slot connection 315 to the feed dog carrier 308. The spring connection 307 and a bowed spring 316 serve to support the feed dog 309 in a substantially horizontal plane. The spring connection 307 is adapted to place the feed dog 309 down into engagement onto the work and the underlying work support 36 or throat plate 87 for one type of auxiliary oscillatory feed or to be forced down into engagement with the feed dog 65' as indicated by dot-and-dash lines in Fig. 13, the bowed spring 316 allowing the carrier 308 to move downwardly into a parallel position with the underlying work and mating part. Similarly, the eccentric 304 imparts a clockwise rotation to the lever 312 about the pivot 313 in order to move the carrier 308 and associated feed dog 309 in a work feeding direction when the spring connection 307 has moved the feed dog into operative engagement with the work. Upon further rotation the eccentric 303 through the spring connection 307 lifts the feed dog 309 from the work, and the lever 312 is then oscillated by the eccentric in a

counter-clockwise direction, to move the feed dog 309 into a forward position again for feeding a following section of the work. By lifting the pivot 313 in the slot 314 and then tightening it, the distance between the pivot 313 and the eccentric 304 is shortened and thereby a greater extent of feeding movement is imparted to the carrier 308 and vice versa.

Thus four different auxiliary operation units have now been described in Figs. 6 through 13 for four different types of operations, all or any one of which may be secured to the various sides of the horn 205'; all of which may be operated in unison with the reciprocating needle, looper, or feeding mechanism; and all of which may be free of each other either in securing them to the horn or in their operating relationship to the work or in their relation to main operating mechanisms.

Figs. 14 and 15 illustrate another form of auxiliary feeding unit 318 of the so-called rotary wheel type. In some forms of work it is desirable to have a serrated wheel press onto or into the work thereby to feed it in absolute unison with the underlying feed dog 65. The auxiliary driving mechanism 204 of the present invention makes possible an extremely simple mechanism for this purpose.

In its present preferred form this comprises a main frame 319, adapted to be secured to the rear wall 231 of the horn 205' with screws 254, having a rearward extension 320 supporting a conventional ball or roller type clutch 321 and a downward extension 322 supporting an intermediate driving mechanism 323. The latter extension supports a slide 324 carrying a feed wheel 325 with a serrated feeding edge 326 in the form of right angle helical teeth engaging with right angle helical teeth of a lower gear 327 driven by a shaft 328 and upper gear 329 associated with a large gear 330 secured to a shaft 331 projecting downwardly from the clutch 321.

Step-by-step rotary movement to the clutch 321 and to the feed wheel 325 through the gears just described is accomplished by a lever 332 pivoted on a stud 333 and a finger 334 engaging with a slot 335 in the cover plate 336 of the clutch when an eccentric 337 on a sleeve 338 secured to the projecting end of the upper horn shaft 239 is rotated. The extent of movement given to the feed wheel 325 and to the clutch 321 is varied by moving the pivot 333 into various vertical positions in the slot 340.

The slide block 324 is held in a suitable channel section of the lower extension 322 by a suitable plate 341 and is urged toward the underlying work and feed dog by a spring 342 with the desired degree of pressure. Also, a pin 343 is provided in the slide to engage with the notch 344 in the presser bar 60 in order to be lifted away from the work support conjointly with the regular presser foot either by the foot control or the hand control 67 as will be apparent by viewing Fig. 15.

In some instances it may be preferable to mount an auxiliary operation unit on one side of the machine and have it operated by a driving mechanism on another side of the machine. Such an embodiment is illustrated in Figs. 16, 17, and 17A, comprising a ruffer unit 346 with a variable feed mechanism 347. In detail it comprises a base member 348 secured to the front wall 230 of the horn 205' with screws 254 having an integral arm 349 supporting a pin 350 which is provided with an arm 351 secured thereto with a yoke 352 having a spring finger 353 at its lower

end, which, so far, is very similar to the ruffling mechanism as shown in Figs. 6 and 7.

However, at its opposite end the pin 350 is provided with an arm 354 having a T shaped slot 355 adapted to accommodate a slide block 356 with a plunger pin 357, this plunger being adapted to enter various notches 358, 359, and 360 for a one-to-one, two-to-one, and three-to-one ratio of feeding movement to the ruffer blade 353 relative to the regular feeding mechanism 35 of the sewing machine.

An eccentric 361 on the outer end of the extension rod 207' accommodates a crank arm 362 which at its other end is connected to a shank 363 on the slide 356 and thereby imparts oscillatory movement to the arms 351 and 355 and to the blade 353 each time the main drive shaft 117 is rotated.

A sleeve 364 is provided with a bore 365 adapted to clear the extension shaft 207' and to set upon a concentric shoulder 366 of the eccentric 361 at one end and upon a collar 367 at its opposite end, and is provided with a link connection 368 to an arm 369 to control the differential feed mechanism 347. An arm 370 is preferably connected to any foot pedal arrangement by a wire 371 as shown in Fig. 17. The link connection 368 includes the arm 369 fixed to the outer end of the sleeve 364 having a pin connection 372 to a link 368 which in turn has a pivotal mounting upon the shank 363 of the slide 356 as shown in Fig. 17.

The link 368 pivoted on the stud 372 serves to move the slide 356 and plunger 357 vertically in the T slot 355 to any of the notches 358, 359, and 360 and also allows the arm, driven by the eccentric 361, to impart oscillatory movement to the arm 354 and to associated parts.

Any of the now well known foot controls may be secured to the arm 370 at the opposite end of the sleeve 364 in order to move the arm 369 and associated slide 356 into the desired station. A spring 374 is preferably provided between the arm 370 and the upper arm 31 of the sewing machine to pull the slide into the lower most position with the plunger 357 in the notch 358 for a one-to-one ratio of feed. As the foot pedal or an auxiliary hand lever is moved the plunger may be moved into the two-to-one notch 359, or into the three to one notch 360. These ratios are merely illustrative and may be 5 to 1—10 to 1, and other ratios as desired.

Modified auxiliary drive

With the auxiliary driving mechanism 204 so far described and the transmission 237 it is possible to change a unit from one side to one other side; for example, to change the trimming mechanism shown in Figs. 8 and 9 from the inner side wall 232 to the outer side wall 233. However, it is not possible to place this same unit onto either the front wall or rear wall 230 and 231 respectively, because the drive shaft 239 is in an upper corner of the walls 230 or 231 rather than substantially in the center of the wall, e. g. shaft 238 in walls 232 and 233. Similarly, it is not possible to move the thread controlling device of Figs. 10 and 11 to either of the side walls 232 or 233 or to the front wall 230. Because the driving connection is in the upper left hand corner of the unit as viewed in Fig. 10 the driving shaft 239 would engage a solid section of the upper right hand corner of the unit if an attempt was made to secure it to the front wall 230 of the horn 205'.

While it is true that this does not represent a major handicap since the cost of the auxiliary operation units is very small and the place of connection more or less standardized, it is desirable in some types of manufacturing set-up to be able to change the units from one side to the other and therefore it would be a real advantage to have the auxiliary operation units fully universal or fully interchangeable on the four sides of the support.

Figs. 18 through 21 disclose a modified form of auxiliary drive in which these desirable fully universal characteristics may be obtained and wherein a driving connection projects from all four of the walls 230 through 233 at a substantially central point so that an auxiliary operation unit on one side may be moved to any one of the three other sides for use. This modified form of drive 204' includes a plurality of beveled gears 375, 376, 377, and 378 mounted for axial and rotary movement in suitable bearings 379 in each of the side walls 230 through 233 of the horn 205'. The beveled gears 376 and 378 in the side walls 232 and 233 are provided with a stud 380 having a solid pin connection 381 to the gear 376 and having a key 382 and slot 383 connection to the other gear 378 which makes possible the use of the extension shaft 207' already described in detail which has the splined connection 250 with the beveled gear 376 in a bore 384 thereof. The stud 380 is of small enough diameter to clear between the presser bar and the needle bar; thus, the beveled gears 376 and 378 are rotated coordinately in unison with the extension shaft 207'.

The beveled gears 375 and 377 on the front and rear walls 230 and 231 of the horn 205' may be meshed with either of the side bevel gears 376 and 378 in order to effect R. H. or L. H. rotation; viz., when meshed with the beveled gear 376, as shown in Figs. 18 through 20, rotation of one hand occurs, and if meshed with the beveled gear 378, rotation of the other hand occurs and in any event all four gears may, through the stud 380, be rotated coordinately.

As shown in Fig. 20 the gears 375 and 377 are meshed with the beveled gear 376 in order to be driven by the latter, and the remaining beveled gear 378 is mounted in an inoperative position relative to these two driven gears by pulling a shank 385 thereof outwardly relative to the wall 233 and by tightening a screw 386 and collar 387 in a secondary notch 388 whereupon the beveled gear 378 serves merely to provide a bore or socket 384 to operate any device attached to the side wall 233. The beveled gear 376 may likewise be shifted to an out position whereupon the beveled gear 378 may be moved to an in position with the set screw 386 in a primary notch 389 whereupon it serves as a socket to drive units on the side wall 233 and to drive either or both of the bevel gears 375 and 377 and auxiliary working units associated therewith. If desired to use only the front or the rear bevel gear 375 or 377 as a driver for such an auxiliary unit the unused front or rear bevel gears may be moved to, and maintained in the inoperative position by the collar 387.

The presser bar, needle bar, controlling and operating mechanisms therefor, and the feeding mechanism of the sewing machine may be the same as has already been described in detail and it is therefore felt that further detailed description seems unnecessary in connection with this modified form of drive shown in Figs. 18 through 21.

Modified cam, gear, and like driving elements may be used advantageously with this modified auxiliary driving mechanism and are briefly shown in Fig. 21.

- 5 Any of the beveled gears 375 through 378 are held in the operative position with the collar 387 out on the shank 385, with the set screw 386 in the primary notch 389, and with the collar against the wall by any suitable counterbore 10 390 with a flange like section 391 on the base of the unit being used, the latter allowing rotary and preventing axial movement of the collar and gear. This, or any modified form of this counterbore on the base of the auxiliary operation 15 units serves this purpose and will be clearly understood by reference to Fig. 21G. Further, this counterbore may be modified to accommodate and retain various driving elements in the socket 384.
- 20 This feature of the invention can be clearly understood by reference to Figs. 21A, B, D, and G which illustrate how the counterbore 390 on the base 253' (e. g. modified support for the ruffer shown in Figs. 6 and 7) would be used in this form of the invention. The counterbore 390 engages the collar 387 keeping the bevel gear 375 in engagement with either the side gears 376 and 378 whereupon it is merely necessary to slide a shank 392 with a key 393 of an eccentric 273' 25 into the socket 384 of the bevel gear in order to provide an eccentric driving connection for the remainder of the ruffling apparatus shown in Figs. 6 and 7.

If preferred, the base member 253' may be provided with an integral cast or a pressed metal flinger 394 as shown by dot-and-dash lines in Fig. 21—G in order to engage the outer end of the eccentric element 21D to prevent it from working out of the socket. The gear 395 shown in Fig. 40 21—C may be similarly held in place, or like the eccentric shown in Fig. 21—E and the pin and plate driver shown in Fig. 21—F, may preferably be held in place primarily by having a counterbore, similar to the counterbore 390 but of sufficient depth so that the flange 391 sets over the flange-like sections 396 and 397, thereof, to 45 retain these driving elements and the associated beveled gear in operative position. These changes are but minor matters of depth or proportion well within the scope of mechanics in this art and it is thought that further description is unnecessary.

Figs. 22 and 23 illustrate the trimming device secured to the work support and have been described in detail hereinbefore.

55 Figs. 24 and 25 illustrate a further form of auxiliary operation unit advantageously made possible by either of the auxiliary driving mechanisms of the present invention. It illustrates the advantages of the rotary auxiliary drive shaft provided by the present invention (even though the upper arm and lower arm shafts are all of the oscillatory and reciprocatory type).

This unit 400 comprises a base member 401 60 secured to the rear wall 231 of the horn 205' provided with a rear extension 402 supporting an intermediate shaft 403 having a worm gear 404 at its upper end meshing with a worm 405 secured to the projecting end of the upper horn shaft 239 65 as by a screw 406 and having an eccentric 407 at its lower end engaging with a slot 408 in the rear of a lever 409 so as to oscillate the latter about a pivot screw 410 and thereby to move a guide sleeve 411 at the front end thereof laterally relative to the line of stitching and to the

line of feed. This sleeve guides a tape or the like in order to obtain a so called serpentine effect, for the sleeve is moved slowly and carries the center of a tape to the right and to the left of the line of stitching, like a ric rac braid.

5 A slot 412 in a lower extension 413 of the base member 401 provides a sturdy support for the lever 409 in its oscillatory movement and a suitable aperture 414 is provided in the lever to clear the needle and presser bars.

10 Although the present invention has been illustrated and described in connection with auxiliary operation units securable to the different sides of a horn on the upper arm, and even though the invention has great utility because of the 15 manner in which these working units may be secured one or more interchangeably on the arm 31, it is within the purview of this invention to provide sewing machines in which the operating units may be made integral with the arm and 20 still have the advantage of the unique substantially direct drives provided by the present invention.

25 However, such a rigid structure would tend to negative the primary object of the present invention for the machine would not be clear of these units when it is desired to use it for just plain stitching operations. Also, the support 205 need not be in the form of a horn 205' with four sides 230 through 233 for conceivably it might be 30 made on the front, end, and back walls of a large cross section upper arm without a downwardly projecting horn, but in such an event the advantageous inner wall 232 would be lacking. The present preferred structure has been illustrated 35 and described.

Other variations and modifications may be made within the scope of this invention and portions may be used without others.

Having thus explained the nature of our invention and described a way of constructing and using the same, although without attempting to set forth all the forms in which it may be made, or all of the modes of its use, we claim:

40 1. In a sewing machine the combination of a 45 frame; sewing mechanism; feeding mechanism; a main driving mechanism including a plurality of crank arms; a trunk in said frame having side openings adapted to pass and receive said driving mechanism with the crank arms from a point exteriorly thereof to a point within and having at least one vertically located opening to connect the cranks to said sewing and feeding mechanisms; means for closing said side openings and for supporting said driving mechanism within the trunk; and other means for closing the vertically located opening.

50 2. In a sewing mechanism the combination of a frame; an upper arm; a lower arm; sewing mechanism; feeding mechanism; driving mechanism; a trunk between the upper and lower arm; and a main drive shaft in said driving mechanism substantially midway of and parallel with the upper and lower arms, adapted to operate said sewing and feeding mechanisms.

55 3. In a sewing machine the combination of a frame; sewing mechanism; driving mechanism; a main drive shaft; a pair of ball bearings on said main drive shaft; a trunk in said frame having a pair of side openings; and means adapted to locate and support said main drive shaft and associated ball bearings in the side openings of the trunk and to prevent axial movement of the main drive shaft.

60 4. In a sewing machine the combination of a

frame; sewing mechanism; a main driving mechanism; a main drive shaft in said driving mechanism; an auxiliary operation unit; and an extension shaft on said main drive shaft adapted to operate said unit coordinately with the sewing mechanism.

5. In a sewing machine the combination of a frame having upper and lower arms and an intermediate trunk; a work support on said frame; a sewing mechanism; a main driving mechanism; an auxiliary operation unit on said work support; a main drive shaft in said trunk substantially midway between the upper and lower arms; and an extension shaft on said main drive shaft forming an auxiliary drive for said unit.

6. In a sewing machine the combination of a frame having upper and lower arms and an intermediate trunk; a sewing mechanism; an auxiliary operation unit; a support on said upper arm for said unit; a main drive shaft in said trunk substantially midway between the upper and lower arms; and an extension shaft on said main drive shaft forming an auxiliary drive for said unit.

7. In a sewing machine the combination of a frame; sewing mechanism; main driving mechanism; an upper arm; an auxiliary operation unit; a wall on the upper arm adapted to support said auxiliary operation unit; and auxiliary driving mechanism adapted to operate the unit supported on said wall.

8. In a sewing machine the combination of a frame; sewing mechanism; driving mechanism; a plurality of walls on said frame; an auxiliary operation unit attachable to one of said walls; an auxiliary transmission mechanism within said walls; and means connecting said transmission mechanism and said auxiliary operation unit to said main driving mechanism for coordinate operation.

40 9. In a sewing mechanism the combination of a frame having upper and lower arms and an intermediate trunk; sewing mechanism; feeding mechanism; driving means for said sewing and feeding means including only oscillatory and reciprocating shafts in the upper and lower arms; a main drive shaft adapted to operate the driving means; an auxiliary operation unit; and an extension shaft on said main drive shaft having completely rotary movement, adapted to operate the auxiliary operation unit.

10. In a sewing machine the combination of a frame; sewing mechanism; a main driving mechanism; walls on said frame; an auxiliary driving mechanism within said walls and associated with the main driving mechanism; an auxiliary operation unit on one of said walls; a driving member between said auxiliary driving mechanism and said auxiliary unit; and means for altering the direction of rotation of said member while the main driving mechanism rotates in only one direction.

11. In a sewing machine the combination of a frame; an upper arm; walls on the upper arm adapted to support auxiliary operation units; a sewing mechanism; main driving mechanism; an auxiliary driving mechanism, adapted to operate the auxiliary units; and interchangeable means in said auxiliary driving mechanism for effecting cam, gear, and other type drives for said units.

70 12. In a sewing machine the combination of a frame; sewing mechanism; main driving mechanism; a support on said frame; a plurality of walls on said support; driving sockets in said walls; an auxiliary operation unit on one of said

walls; a driving member between said socket and said auxiliary operation unit for operating the latter; and auxiliary driving mechanism between said main driving mechanism and said sockets.

13. In a sewing machine the combination of a frame; sewing mechanism; main driving mechanism; a support; a plurality of walls on said support for auxiliary operation units; an auxiliary driving mechanism; and a pair of shafts in said auxiliary driving mechanism at right angles to each other and projecting through and from said walls.

14. In a sewing machine the combination of a frame; a horn on said frame; an inside wall on said horn; an auxiliary operation unit attachable to said wall; sewing mechanism; feeding mechanism; a main driving mechanism; and a shaft extending from said main driving mechanism to said inside wall and adapted to operate the unit on the wall.

15. In a sewing machine the combination of a frame; a sewing mechanism; a main driving mechanism including a main drive shaft; a support on said frame; auxiliary operation units on said support; an auxiliary driving mechanism in said support associated with said units; and a shaft extending from said main drive shaft to said auxiliary driving mechanism.

16. In a sewing machine the combination of a frame; a sewing mechanism; a main driving mechanism; walls on said frame; auxiliary operation units interchangeably securable to said frame; and means associated with said main driving mechanism adapted to operate said interchangeable units.

35 17. In a sewing machine the combination of a frame; a horn on said frame; walls on said horn; sewing mechanism; a main driving mechanism; auxiliary operation units adapted to be secured to said walls; and means adapted to drive said auxiliary operation units on two or more walls.

18. In a sewing machine the combination of a frame; sewing mechanism; a main driving mechanism; a horn having inside and outside walls; auxiliary operation units securable to said walls; and a drive shaft extending from said main driving mechanism through said walls and adapted to operate said units.

40 19. In a sewing machine the combination of a frame; sewing mechanism; driving mechanism; a main drive shaft; a pair of bearings on said main drive shaft; a trunk in said frame having a pair of side openings; and means adapted to locate and support said main drive shaft and associated bearings in the side openings of the trunk and to prevent axial movement of the main drive shaft.

45 20. In a sewing machine the combination of a frame; sewing mechanism; a main driving mechanism; a main drive shaft in said driving mechanism; an auxiliary operation unit; and an extension on said main drive shaft adapted to operate said unit coordinately with the sewing mechanism.

50 21. In a sewing machine the combination of a frame having upper and lower arms and an intermediate trunk; a work support on said frame; a sewing mechanism; a main driving mechanism; an auxiliary operation unit on said work support; a main drive shaft in said trunk substantially midway between the upper and lower arms; and an extension on said main drive shaft forming an auxiliary drive for said unit.

55 22. In a sewing machine the combination of a frame having upper and lower arms and an intermediate trunk; a sewing mechanism; an auxiliary

75

operation unit; a support on said upper arm for said unit; a main drive shaft in said trunk substantially midway between the upper and lower arms; and an extension on said main drive shaft forming an auxiliary drive for said unit.

23. In a sewing machine the combination of a frame; sewing mechanism; driving mechanism; a wall on said frame; an auxiliary operation unit attachable to said wall; an auxiliary transmission mechanism within and adjacent said wall; and means connecting said transmission mechanism and said auxiliary operation unit to said driving mechanism for coordinate operation.

24. In a sewing mechanism the combination of a frame having upper and lower arms and an intermediate trunk; sewing mechanism; feeding mechanism; driving means for said sewing and feeding means including only oscillatory and reciprocatory shafts in the upper and lower arms; a main drive shaft adapted to operate the driving means; an auxiliary operation unit; and an extension on said main drive shaft having completely rotary movement, adapted to operate the auxiliary operation unit.

25. In a sewing machine the combination of a frame; sewing mechanism; a main driving mechanism; an auxiliary driving mechanism; an auxiliary operation unit; a driving member between said auxiliary driving mechanism and said auxiliary unit; and means for altering the direction of rotation of said member even though the main driving mechanism rotates only in one direction.

26. In a sewing machine the combination of a frame; sewing mechanism; main driving mechanism; a support; a plurality of walls on said support for auxiliary operation units; and an extension on said main driving mechanism extending to

at least one of said walls to operate an auxiliary operation unit on the wall.

27. In a sewing machine the combination of a frame; sewing mechanism; main driving mechanism; a support; a plurality of walls on said support for auxiliary operation units; auxiliary driving mechanism; members in said driving mechanism at an angle to each other and in said plurality of walls; and beveled gears for effecting coordinate operation of said members.

28. In a sewing machine the combination of a frame; sewing mechanism; main driving mechanism; a support; a plurality of walls on said support for auxiliary operation units; auxiliary driving mechanism; members in said driving mechanism at an angle to each other and in said plurality of walls; and a worm and worm gear for effecting coordinate operation of said members.

29. In a sewing machine the combination of a frame; an upper arm on the frame; a horn on the upper arm; a plurality of walls on said horn, for supporting auxiliary operation units; auxiliary driving mechanism; and members in said auxiliary driving mechanism in said plurality of walls and at an angle to each other.

30. In a sewing machine the combination of a frame; a main driving mechanism; an upper arm adapted to support auxiliary operation units; an auxiliary driving mechanism associated with said upper arm; and an intermediate shaft adapted to connect said main and auxiliary driving mechanisms, and to be connected and disconnected to these without disturbing same.
